Primary Examiner — Caron D Veynar*Assistant Examiner* — Mehri Bajoul(74) *Attorney, Agent, or Firm* — Themis Law(57) **CLAIM**

The ornamental design for a table, as shown and described.

DESCRIPTION

FIG. 1 is a front elevational view of a table showing my new design;

FIG. 2 is a rear elevational view thereof;

FIG. 3 is a left side elevational view thereof, the right side being a mirror image;

FIG. 4 is a top plan view thereof; and,

FIG. 5 is a bottom plan view thereof.

The portion of the drawing in broken lines is for illustrative purposes only and forms no part of the claimed design.

1 Claim, 5 Drawing Sheets(56)
